UNITED STATES PATENT OFFICE.

ROBERT E. BRAKEY, OF VENTURA, CALIFORNIA.

TRAFFIC-REGULATOR.

1,282,673.

Specification of Letters Patent. Patented Oct. 22, 1918.

Application filed August 1, 1916. Serial No. 112,546.

To all whom it may concern:

Be it known that I, ROBERT E. BRAKEY, a citizen of the United States, residing at Ventura, in the county of Ventura and State 5 of California, have invented new and useful Improvements in Traffic-Regulators, of which the following is a specification.

This invention relates to a traffic regulator, and particularly pertains to a resiliently supported traffic regulating semaphore adapted 10 to be used at street intersections to indicate the directions of travel therefrom.

It has been common practice in many 15 cities to place a vertical semaphore standard at the intersections of street crossings with suitable semaphore arms thereupon to indicate direction of travel. These standards have in most instances been rigidly held and were often damaged by vehicles accidentally 20 striking them. It is the principal object of this invention to provide means for securing the standard in a vertical position under normal conditions and to allow it to yield when struck by a vehicle thus permitting the 25 vehicle to pass by without damage to the standard or vehicle.

Another object is to provide a standard 30 which will instantly return to its normal vertical position when the pressure of the 35 vehicle against it has been removed.

Another object is to provide a simple protecting means which is adapted to protect the internally positioned resilient member from becoming damaged when the standard 40 is in a horizontal or angular position.

Another object is to provide the standard 45 with a series of outwardly extending semaphore members which will be drawn within the standard in an automatic manner as the 50 standard is moved from its vertical position and thus will protect them from damage as well as allow the standard to be forced flat upon the pavement if necessity requires.

Another object is to provide gravity operated 55 means for returning the support to the semaphore arms to their indicating position when the standard returns to the vertical.

It is a further object to provide a device 60 of the character described which will be simple in construction and will perform its functions without requiring frequent repair.

Other objects will appear hereinafter.

The invention is illustrated, by way of 65 example, in the accompanying drawings in which:

Figure 1 is a view in vertical section as taken through the center of the semaphore standard and its base plate and particularly illustrates the normal position of the vital 60 parts of the device as well as a dotted line position in which the device is shown as disposed at an angle to the vertical.

Fig. 2 is a view in vertical section illustrating the semaphore operating element 65 disposed at the lower end of the standard.

Fig. 3 is a view in perspective disclosing the operative position of the semaphore at a street intersection.

Referring more particularly to the drawings, 10 indicates a tubular semaphore standard which is here shown as closed at its upper end and open at its lower end. The lower end of the standard is adapted to bear upon a base plate 11 which is suitably secured within the surface of the pavement. The base plate 11 is formed with a vertically extending frusto-conical core 12 which is closed at its upper end and there is formed in the configuration of a hemisphere. An 80 opening is made through the spherical end for the reception of a semaphore operating cable 23. The core 12 is adapted to extend upwardly within the open lower end of the standard 10 and is surrounded by a helical 85 spring 13 which is secured thereto in a suitable manner and extends upwardly within the standard to a point adjacent a clamping plate 14 to which it is adjustably secured by eye bolts 15 which extend downwardly 90 through the plate and are secured to the end of the spring. The length of the spring intervening between the base plate and clamping plate is sufficient to maintain the standard in an upright position and to allow it 95 proper resiliency to be forced from the perpendicular to a horizontal or intermediate position.

Referring particularly to Figs. 1 and 2 of the drawings, it will be seen that a 100 series of semaphore arms 16 are pivotally mounted upon pins 17 within the upper end of the standard and that the arms extend radially therefrom through longitudinal slots 18 in the wall of the standard. 105 These arms normally extend horizontally and are positioned to indicate the paths of travel emanating from a street intersection. It is however desirable to draw the arms 16 into the casing at times when the 110 standard is moved from its vertical position. This is accomplished by means of a

rigid actuating rod 19 which is formed with an eye 20 at its upper end adapted to be engaged by connecting links 21, one of which is secured to the end of each of the 5 arms 16. The other end of the rod 19 is formed with an enlarged portion 22 which normally is seated upon the upper face of the core 12. Suitably secured within the portion 22 is the depending 10 flexible cable 23 to the lower end of which is connected a weight 24 for a purpose hereafter to be described. The weight 24 is adapted to move within the core 12 which is hollow and a pit 25 formed below 15 the plate 11.

In operation, the standard will normally be maintained in a vertical position due to the action of the spring 13 as it draws 20 downwardly upon the clamping plate 14 and seats the standard upon the plate 11 in a firm manner. Simultaneous with this action is the action of the actuating rod 19 which is formed to bear by its enlarged portion 22 upon the upper face of the core 12; the rod and its links being of the 25 proper length to maintain the semaphore arms in horizontal alinement. When, by a cause, the standard 10 is struck it will instantly yield and swing away from the 30 object striking it. This movement is allowed by the resiliency of the spring 13 which resiliency is adjustably controlled by the adjusting bolts 15 extending through the clamping plate 14. As the standard swings 35 it will bear upon some point along the marginal lower edge of the wall of the standard and will cause the open end of the standard to swing upwardly and over the core 12. As this occurs, the rod 19 will be drawn out- 40 wardly due to the change in centers of the standard and will be opposed by the weight 24 which will immediately draw the semaphore arms to a shielded position within the standard; a flexible cable at this time will 45 allow angular movement of the arm 19 without binding and will also compensate for the movement of the semaphore arms away

from the core. Return movement of the standard will cause the enlarged portion 22 of rod 19 to be brought to bear against the 50 cone and force the arms outwardly to their horizontal position.

It will be noted that the time the semaphore standard is swung away from its vertical position, the lower end of the coil 55 spring 13 will be uncovered and is liable to be damaged by the wheel of the vehicle. At this time the core 12 will reinforce the spring and support it in such a manner that it is not liable to become crushed or otherwise damaged.

It will thus be seen that the indicator here provided will act in a positive manner to maintain a set of semaphore arms in a signaling position and that it will yield from 65 external pressure to prevent damage to itself or to the object which has encountered it and that while so yielding it will automatically draw its semaphore arms into concealed positions thereafter returning them 70 to their normal positions as the standard returns to the vertical.

I claim:

A traffic regulator, comprising a tubular upright standard, a base upon which said 75 standard rests, a resilient member adapted to secure the standard upon its base and permitting the standard to swing from the vertical, a series of semaphore arms pivotally mounted within the upper end of said 80 standard and adapted to extend outwardly therefrom, means for swinging the arms to a shielded position within the standard as said standard is swung from the vertical, means for returning the arms to their outwardly extending positions when the standard returns to its normal vertical position, and means for protecting the lower end of the resilient member when uncovered by the 85 lower end of the swinging standard. 90

In testimony whereof I have signed my name to this specification.

ROBERT E. BRAKEY.
